BELT

L. Preston Hollander, Jr., New York, N. Y.

Application November 2, 1949, Serial No. 5,827

Term of patent 7 years

(Cl. D3—10)

To all whom it may concern:

Be it known that I, L. Preston Hollander, Jr., a citizen of the United States of America, residing in New York, county of New York, and State of New York, have invented a new, original, and ornamental Design for a Belt, of which the following is a specification, reference being had to the accompanying drawing, forming part thereof,

Fig. 1 is a front perspective view of a belt, showing my new design.

Fig. 2 is a perspective view of the belt illustrating the inside adjustable closing.

Fig. 3 is a fragmentary view of the rear portion of the belt illustrating the adjustable closing in detail.

I claim:

The ornamental design for a belt, substantially as shown and described.

L. PRESTON HOLLANDER, JR.
